E. F. ANDREWS

CARBURETOR

Filed Aug. 3, 1917

INVENTOR:
EDWARD F. ANDREWS.

ATTORNEY:
George Bayard Jones.

UNITED STATES PATENT OFFICE.

EDWARD F. ANDREWS, OF CHICAGO, ILLINOIS, ASSIGNOR TO UNIVERSAL ENGINEERING COMPANY, OF MAYWOOD, ILLINOIS, A CORPORATION OF ILLINOIS.

CARBURETOR.

Application filed August 3, 1917. Serial No. 184,205.

To all whom it may concern:

Be it known that I, EDWARD F. ANDREWS, a citizen of the United States, residing at Chicago, in the county of Cook and State of Illinois, have invented a certain new and useful Improvement in Carburetors, of which the following is a full, clear, concise, and exact description.

This invention relates to carburetors and 10 more particularly to carburetors of the type adapted for use in connection with hydro-carbon engines.

It is well known that in the use of carburetors in which fuel is raised from a low level 15 main supply tank directly to the carburetor spray nozzle by the partial vacuum created in the carburetor by the engine intake suction, the change of fuel level in the supply tank changes the richness of the mixture entering the engine, unless some needle valve 20 adjustment is provided which is frequently adjusted during the change in level of fuel in the low level supply tank.

Gravity feed carburetors supply with constant level float chambers are not subject to 25 this defect, but are objectionable because of the dangers and inconvenience caused by flooding due to leaky or dirty float valves.

The object of the present invention is to 30 provide a suction feed carburetor arranged for raising the fuel from a low level supply tank to the level of the carburetor, in which means are provided so that the effective lift of fuel from the low level tank to the carburetor does not vary with the change of fuel 35 level in the low tank.

In carrying out my invention I provide a standpipe which extends upwardly from the low level chamber, and which rises and falls 40 with the fuel in the supply tank, so that the effective lift of fuel through the standpipe is always the same. I also provide what I term a rain chamber, into which the fuel is delivered from the upper end of the said 45 standpipe, and in which the fuel falls in the form of mist or rain, the result being that while the fuel may be lifted to a higher point under some conditions than others, the fall of the fuel in the rain chamber 50 exerts no energy on the rising column of fuel in the standpipe, so that the suction required for delivering a specific amount of fuel up the standpipe and permitting that amount to fall into the bottom of the rain 55 chamber is exactly the same whether the

standpipe is delivering to a point near the top of the rain chamber, or to a point near the bottom thereof.

In carrying out my invention I preferably construct the rain chamber at least partially 60 of glass, so that the fuel delivery may be readily observed.

In one embodiment of my invention the fuel from the rain chamber is drawn through the same opening through which 65 the movable standpipe extends, as under these conditions the movement of the standpipe prevents the accumulation of dirt in the small opening, serving as a fuel delivery port between the rain chamber and the carburetor mixing chamber.

The power output of an internal combustion engine depends upon the quantity of combustible mixture drawn into the cylinder at each stroke. The quantity of mixture is 75 less when the suction or partial vacuum under which the mixture is drawn into the cylinder is great, than when the suction is only slight. In order that fuel may be lifted to the carburetor with a slight suction, I 80 have found it advantageous to permit a small quantity of air to be drawn into the standpipe at a point near the surface of the fuel in the main tank, thus lightening the rising column of fuel to such an extent that 85 it may be drawn up with less suction. The admission of air at this point also diminishes the delicacy of the carburetor adjustment, because the fuel as delivered to the carburetor, being mixed with air, is in less concentrated form, by reason of which slight variations in the quantity delivered into the incoming stream of air do not change the proportions of the resultant mixture of air and fuel as much as would the same variation in the quantity of a more concentrated fuel.

In the preferred form of my invention I calibrate the vertical portion of the rain chamber so that the upper end of the standpipe may indicate on the calibrations the amount of fuel in the main tank.

A further object of the invention is to provide a carburetor wherein the fuel, as the same is supplied thereto, is visible to 100 the operator, thus enabling him to determine whether or not the carburetor is operating properly, while at the same time means is afforded whereby very accurate adjustments of the carburetor may be made. 110

Many other objects and advantages will be apparent from the following description taken in connection with the accompanying drawings wherein several forms of the invention are illustrated.

Fig. 1 is a vertical sectional view of a carburetor constructed in accordance with the present invention, said carburetor being shown mounted in operative position on a fuel tank.

Fig. 2 is a similar view of a modified form of carburetor.

Fig. 3 is a detailed view illustrating a further modification of the invention, and Fig. 4 is a section on the line A—A of Fig. 1.

The carburetor, several forms of which are illustrated in the accompanying drawings, is particularly adaptable for use with hydro-carbon engines of the stationary type, such, for instance, as those used in connection with storage battery charging systems, although it will be obvious from the following that said carburetor is not limited to this particular use, but may be used in connection with other forms of hydro-carbon engines.

Referring more in detail to the drawings the preferred embodiment of the invention is illustrated in Fig. 1 and as shown, comprises a casting 1 provided with an annular base 2 which affords means whereby the device may be conveniently and preferably rigidly secured to the fuel tank, substantially as shown at 4, said casting comprising an elongated mixing chamber 5 adapted to communicate at one end thereof at 6 with the cylinder or cylinders of the hydro-carbon engine (not shown), the other end 7 thereof being upturned and provided with a suitable adjustable air valve 8 whereby the richness of the mixture supplied to the engine may be regulated. The air valve 8, as shown, comprises a disc held yieldingly against the adjusting nut 9 on the pin 10 by means of the coiled spring 11, said pin being screw-threaded or otherwise mounted in the base 2 of the casting 1. If desired, a lock nut or other suitable means may be employed to lock the adjusting nut 9 in its adjusted position. From the above it will be noted that in starting the engine an extremely rich priming mixture may be supplied thereto by merely pressing said disc down over the upturned end 7 of the casting 1, thereby cutting off the air entirely or any desired portion of it, as may be desired. It will be readily noted that this depression of the disc in addition to diminishing the supply of air also increases the supply of fuel, owing to the increased suction in the carburetor caused by such depression. As soon as the engine is started, the disc is released, the spring 11 forcing the same back to its normal adjusted position. In

view of the construction of the air valve and the relative arrangement of its parts it will be noted that the reverse blast of fuel which results in the event the engine back-fires, will impinge against the under surface of the disc as a result of which a large amount of said fuel will be directed back into the mixing chamber thereby avoiding waste, while that which is blown out will be discharged downwardly by the downturned edge of the disc, instead of being forced up into the operator's face, as is commonly the case.

Communicating with the mixing chamber 5 near the end 6 thereof by means of a small aperture 12 is a suitable priming cup 13 adapted to afford means whereby, in the event the hydro-carbon engine is operated on kerosene, said engine may be primed with gasoline in starting the same.

Mounted uprightly on the casting 1 and preferably intermediate the priming cup 13 and the air valve 8 is a tubular member 14 adapted to receive a clear vision tube 15 preferably of glass. This glass tube 15 is clamped securely in position within the member 14 between suitable gaskets 16 by means of the screw cap 17 adapted for engagement with the upper end of said member 14. The tubular member 14 is preferably provided with vertical slots 18 (see Figure 4) through which the action of the carburetor may be viewed.

Mounted within the fuel tank 3 is a suitable float 19, said float being provided with a stand pipe 20 preferably of small bore, said pipe being adapted to project upwardly from the float through apertures 21 and 22, formed in the walls of the casting 1, into the fuel or rain chamber 23 formed by the glass tube 15. The pipe 20 is made to fit snugly within the aperture 21, but at the same time slides freely therein to permit of said pipe rising and falling with the float 19. The aperture 22, however, is constructed slightly larger than the diameter of the pipe 20 so as to provide a slight clearance therearound which forms the discharge or atomizing nozzle of the carburetor.

The operation of the carburetor is substantially as follows:

On each suction stroke of the engine a partial vacuum, or reduction in pressure is created in the chamber 23 as a result of which fuel is drawn from the tank 3 up through the pipe 20 into said chamber 23, the fuel descending to the bottom of said chamber from whence it is sprayed out through the atomizing nozzle 22 into the mixing chamber 5. In the chamber 5 it is thoroughly mixed with the air supply which is drawn in past the valve 8, said mixture being then charged into the cylinder or cylinders of the engine. It is obvious from the foregoing that the standpipe 20,

being mounted on the float and adapted to move therewith, rises and falls within the chamber 23 with the rise and fall of the level of the fuel within the tank 3. Accordingly, 5 if desired, a suitable graduated scale, such as shown at 14^a, may be provided on the tubular member 14 whereby the rise and fall of said standpipe 20 may be utilized to indicate the level of the fuel within said 10 tank 3. If desired, the scale may be etched or otherwise placed directly on the glass tube 15. It is obvious from the foregoing that the operation of the carburetor is substantially the same regardless of the level 15 of the fuel within the tank 3, the only difference occasioned by variations in the level of the fuel being in the distance the fuel falls from the upper end of the pipe 20 to the base of the chamber 23 as the same is 20 drawn upwardly through said pipe by the suction of the engine. In other words, the fuel falls a greater distance when the tank is full than when the same is partly empty. This, however, it will be noted, has no 25 effect whatever on the uniformity of the mixture drawn into the engine as the mixing is effected within the chamber 5 as the fuel is sprayed into said chamber through the nozzle 22. During the operation of the 30 carburetor, the fuel is sprayed upwardly into the chamber 23 from the upper end of the pipe 20 in much the same manner as water would be sprayed upwardly in a small fountain. This action is clearly visible 35 through the vertical slots 18 and the glass tube 15. Accordingly, it may readily be determined whether the carburetor is operating properly without removing any of its parts or dismantling it in any way. Furthermore, 40 as the lubricating medium for the engine may, if desired, be mixed with the fuel and thus conveyed to the various bearings, the operation of the carburetor, as viewed through the glass tube, also indicates to the operator whether the engine is 45 being properly lubricated.

In Fig. 2 is illustrated another form of the invention wherein a slightly modified form of standpipe 20 is provided, said pipe 50 having its lower end upturned as at 24, and projecting above the level of the fuel within the tank 3, the end of said projection 24 being open as shown at 25, whereby air may be drawn into said pipe and mixed 55 with the fuel as the same is drawn in through the aperture 26 formed in the portion of the pipe which projects beneath the surface of the fuel. It will thus be noted that means has been provided whereby an 60 initial mixing of fuel and air is effected in the pipe 20 as the same is drawn upwardly therethrough and prior to its discharge into the chamber 23. From the chamber 23 the partial mixture of fuel and air is 65 drawn downwardly by the suction of the en-

gine and out through the pipe 27 and discharged through the atomizing nozzle 28 into the mixing chamber 29 where it is mixed with the main air which is supplied through the adjustable air valve 30 provided at one end of said mixing chamber. This initial mixing of the fuel with air in the pipe 20 enables the fuel to be raised a greater height by a given amount of suction, owing to the reduced weight of the 75 column of fuel due to the presence of air therein.

In this form of the invention also, a suitable priming cup 32 is provided which communicates with the mixing chamber 29 whereby the engine, if it is desired to operate the same on kerosene, may be primed with gasoline in starting the same.

As a means of supplying the engine with a mixture rich in hydro-carbon when it is 85 desired to start the same, a plunger rod 33 slidably mounted in the casting 1 is provided, said plunger rod being normally held in the position shown in Fig. 2 by means of the coiled spring 34. The lower end of the 90 rod 33 is substantially ring-shaped and is positioned in a plane substantially horizontal, as shown at 35, it being adapted to engage the upper surface of the float 19 to thereby submerge the same and the upper end of the 95 projection 24 of the pipe 20 when the plunger rod is forced down by the operator against the action of the spring 34. This, it will be noted, cuts off the initial supply 100 of air through the opening 25, the suction produced by the engine acting to draw a solid column of fuel upwardly into the chamber 23 whereby a richer mixture is supplied to the engine for starting purposes. After the engine has started, the rod 33 is 105 released, thus allowing the float to resume its normal position, in which position the initial mixture of air and fuel in the pipe 20 is effected prior to its discharge into the 110 chamber 23, as above pointed out.

This same result may also be accomplished by the further modification of the invention as illustrated in Fig. 3 wherein means is provided whereby the engine may be automatically primed with a mixture rich 115 in hydro-carbon during its initial operation, said means comprising a small container 36 mounted within the float 19 and provided with a fuel inlet 37. An inlet air pipe 38 communicates with the container 36 and is shown rising therefrom to a point slightly above the upper surface of the float 19. The standpipe 20 in this form of invention is substantially the same as that illustrated in the form shown in Fig. 1 with the exception that the lower end of said pipe is positioned within the container 36, terminating slightly above the fuel inlet 37. It will be noted from this construction that 125 when the engine is at rest, the fuel within 130

the tank 3 being at a level, substantially as indicated, will flow into the container 36, thereby filling the same. Accordingly when the engine is started no air is drawn in 5 through the air supply pipe 38 until the fuel within the container 36 is exhausted. Thus the auxiliary air supply is cut off during the initial operation of the engine and accordingly a much richer mixture of fuel 10 and air is supplied to the engine. After the fuel within the container 36 has been exhausted, however, it will be noted that air is again drawn in through the air supply pipe 38 and is mixed with the fuel as the 15 same is drawn in through the inlet 37 in substantially the same manner as that illustrated and described in connection with the form of invention illustrated in Fig. 2.

The operation of the carburetor shown in 20 these forms of the invention is substantially the same as that heretofore described in connection with Fig. 1 with the exception that a partial mixture of fuel and air is effected, prior to the final mixing of the fuel with the 25 main air supply in the mixing chamber 29.

In all of the forms of the invention herein illustrated, it is obvious that the standpipe 20 may be used as a fuel level indicator and further, that a carburetor has 30 been provided which can under no circumstances leak, owing to the fact that said carburetor is mounted in a plane above the level of the fuel at all times. It is also obvious that in the carburetor herein described the mixture of fuel and air is uniform at all times regardless of the level of the fuel within the fuel tank. Thus, a carburetor has been provided which overcomes the disadvantages of the gravity feed carburetor in that it has no outlet below the level of the fuel in the fuel tank and hence no fuel from said tank can leak through said carburetor. The objections to the 40 standard suction feed carburetors, as above pointed out, are also obviated in the present structure in that no variation in the mixture results from changes in the level of the fuel within the tank.

If desired a small aperture 39 may be 50 provided in the standpipe 20 of Fig. 1 just above the upper surface of the float 19, in order that a partial mixture of air with the fuel as it is drawn upwardly through said pipe may be effected.

This aperture is preferably positioned so 55 that air from the tank may be drawn therethrough into the pipe 20 as the float descends, in much the same manner as the initial mixing is effected in the construction illustrated in Fig. 2. The aperture 39 is preferably of such size that only a small proportion of air can be drawn therethrough, the main mixing being effected in the chamber 5 which is provided with an adjustable air valve 8, whereby the propor-

tion of air and gas mixed in said chamber may be regulated. It is obvious that if the aperture 39 was of sufficient size to permit of a substantial amount of air passing therethrough into the pipe 20 it would be difficult to regulate the amount of fuel drawn up through said pipe and that accordingly it would be difficult to regulate the mixture fed to the engine. The aperture 39 not only affords means whereby a slight initial mixing is effected in the pipe 20, but also enables the fuel to be raised a greater height by a given amount of suction owing to the reduced weight of the column of fuel due to the presence of air therein.

It is apparent that many changes and modifications may be made in the construction herein illustrated and described and the right is therefore reserved to make such changes and modifications as fall within the scope of the appended claims.

Having thus described my invention, what I claim as new and desire to secure by Letters Patent of the United States is:—

1. The combination with a carburetor and a fuel supply tank therefor, at a level below the carburetor, the fuel level in which continuously falls as the fuel is consumed by the engine, of devices through which fuel may be raised from said tank to said carburetor upon each suction stroke of the engine, said devices comprising a tube supported on the surface of the fuel in said tank, and having an opening, through which fuel is supplied thereto, below the level of the fuel in the tank so that the distance through which the fuel is raised remains constant from the full to the empty level of the fuel in said tank.

2. The combination with a main fuel tank wherein the fuel level varies as the fuel is consumed, of a float in said tank, a carburetor comprising a rain chamber and means carried by said float for delivering fuel into said rain chamber at a constant height above the surface of the fuel in said main tank, a mixing chamber, and a passage between said rain chamber and said mixing chamber for delivering fuel from the former to the latter.

3. In a carbureting device for internal combustion engines, the combination with a fuel tank of a float in said tank, a carburetor mounted above said float, a rain chamber, a fuel pipe carried by said float and projecting upwardly into said rain chamber, said rain chamber being subject to reduction in pressure created in the mixing chamber of said carburetor by the suction of the engine whereby fuel is lifted from said tank upwardly through said pipe and sprayed into said rain chamber.

4. In a carbureting device for internal combustion engines, the combination with a fuel tank of a float in said tank, a carburetor

- retor mounted above said float, a transparent fuel chamber, a fuel pipe carried by said float and projecting upwardly into said fuel chamber, said fuel chamber being subject to reduction in pressure created in the mixing chamber of said carburetor by the suction of the engine whereby fuel is lifted from said tank upwardly through said pipe and sprayed into said fuel chamber, and indicating on said fuel chamber relative to fuel supply, whereby the quantity of fuel contained in the supply tank may be ascertained.
5. In a carburetor for hydro-carbon engines, the combination with a fuel tank having a float, of a mixing chamber and a fuel chamber mounted above said tank, a passage between said chambers, a fuel pipe projecting from said float upwardly through one of said chambers and said passage, into the other of said chambers, and means for establishing communication between said chambers, said means being subject to reduction in pressure created in said mixing chamber by the suction of the engine whereby to draw fuel from said tank through said pipe into said fuel chamber, and through said passage into said mixing chamber.
6. In a carburetor for hydro-carbon engines, the combination with a fuel tank having a float, of a fuel pipe carried by said float, and rising upwardly therefrom, a chamber surrounding the upper end of said fuel pipe, a nozzle connected with said chamber having its discharge opening in the base of said chamber, said discharge opening being subject to reduction in pressure created in the mixing chamber of the carburetor by the suction of the engine to draw fuel through said pipe into said chamber and through said nozzle.
7. A main tank wherein the fuel level continuously falls as the fuel is consumed by the engine, a carburetor receiving fuel from said main tank, and means for raising fuel through a constant distance, regardless of the level of the fuel in said tank, and for delivering the same to said carburetor, comprising a tube having its intake opening below the level of the fuel in said main tank.
8. A fuel tank wherein the fuel level continuously falls as the fuel is consumed by the engine, a carburetor comprising a main chamber, a mixing chamber, a single fuel passage communicating therebetween, and means whereby the fuel fed through said passage into said fuel chamber is raised through the same distance regardless of the level within the fuel tank.
9. The combination with a fuel tank wherein the level of the fuel continuously falls as the fuel is consumed by the engine, of a carburetor positioned thereabove, and means for raising fuel from said tank through a constant distance to supply said carburetor, regardless of the level of the fuel within said tank, said means comprising a tube having an intake opening below the level of the fuel in the tank, said tube being subject to reduction in pressure created in the mixing chamber of the carburetor by the suction of the engine.
10. The combination with a fuel tank in which the level of the fuel falls as the fuel is consumed by the engine, of a movable element provided with a fuel discharge port receiving fuel from said tank, means causing said port to rise and fall at a constant height relative to the surface of the fuel in said tank, a chamber wherein the port rises and falls, and wherein the fuel from said port falls by gravity, said chamber having a discharge opening greater than the discharge port in said movable element, said chamber being subject to reduction in pressure created in the mixing chamber of a carburetor by the suction of the engine whereby fuel is drawn into said chamber from said tank and supplied to said carburetor.
11. The combination with a carburetor having a mixing chamber of given diameter of a fuel tank for supplying fuel to said mixing chamber, said tank lying below the level of said mixing chamber, and means for lifting fuel from said fuel tank through a constant distance, and delivering it to said mixing chamber while the level of the fuel in said fuel tank varies through a distance greater than the diameter of said mixing chamber, comprising a tube having an intake opening below the level of the fuel in said tank, said tube being subject to reduction in pressure created in the mixing chamber of the carburetor by the suction of the engine.
- In witness whereof I hereunto subscribe my name this 27th day of July, A. D. 1917.
- EDWARD F. ANDREWS.
